UNITED STATES PATENT OFFICE.

LEMUEL S. BETZER, OF MEMPHIS, MISSOURI, ASSIGNOR OF ONE-HALF TO
HENRY SEAMAN, OF SAME PLACE.

BOILER WASHING-MACHINE.

SPECIFICATION forming part of Letters Patent No. 267,969, dated November 21, 1882.

Application filed August 5, 1882. (Model.)

To all whom it may concern:

Be it known that I, LEMUEL STEELY BETZER, a citizen of the United States, residing at Memphis, in the county of Scotland and State of Missouri, have invented certain new and useful Improvements in a Steam-Boiler Washing-Machine; and I do hereby declare that the following is a full, clear, and exact description of the same, reference being had to the annexed drawings, making a part of this specification, and to the letters and figures of reference marked thereon.

Figure 1 of the drawings is a longitudinal vertical section of my invention; Fig. 2, a cross-section of the same; Fig. 3, a side elevation of the cylinder; Fig. 4, a top plan view of the same with the cover removed, and Fig. 5 a detail view of the cylinder-supporting castings and cam attachment.

This invention relates to certain new and useful improvements in steam-boiler washing-machines in which a cylinder for receiving the clothes to be washed is rotated in a vessel or boiler containing heated water; and the object of the present invention is to produce such a device that will require less water and consequently less fuel to heat the same, less time and labor to do the washing, and from its peculiar construction do little or no damage to the clothes during the process, there being no raw edges against which the clothes may wear or projections of any sort which would catch and tear the garments in the wash. At the same time, the device being simple in its construction, it is easy of manufacture and effective in its operation. These objects I attain by the construction substantially as shown in the drawings and hereinafter described.

In the accompanying drawings, A represents a vessel or tank in which the water is placed to be heated, it having a cover, B, provided with a flange, a, and rim b, all formed of the same sheet of metal, by crimping, thus preventing the leaving of any raw edges, or the necessity of soldering the rim to the flange, also by this means avoiding rust and consequent leakage. The flange a, formed by crimping, is secured by clips c at its several corners, which act as braces to the lid from the points and serve to fill the corners out square, there-

by giving a neat and finished appearance to the lid.

In the center of and secured upon the bottom of the boiler A is the horizontal portion d of a casting, C, having vertical arms e extending up the sides of the boiler and terminating in bearings f for the journals g of the clothes-cylinder D, to take the strain off the boiler, the said journal-bearings extending outside the boiler any desired distance. This casting C is also provided with seats h, to which are attached cams E, for the purpose hereinafter described.

The clothes-cylinder D is placed between two castings, F, having radial arms i. Three arms of each casting terminate in a right-angle bend or toe, k, which overlaps the cylinder, thereby serving to hold the same in position, and also act as braces thereto by taking the strain off of the rivets by which the castings are secured to the wheel. The fourth arms of the castings do not terminate in a bend or toe, but extend above the cylinder, and are provided with holes through which passes a rod, m, which serves, in conjunction with the bends or toes of the next arms toward the right, to hold the upper or smaller section, G, of the cylinder in place, and at the same time allow of its ready removal for the purpose of putting in or taking out the clothes from the said cylinder without the use of hinges or catches, which are liable to become rusted and break off, thereby rendering the device inoperative. The centers of the castings F are provided with sockets n, in which fit the journals g. Upon the interior faces of the larger portion of the clothes-cylinder D are placed sudsing-boards H, held in place by rods I, which pass through said sudsing-boards, the cylinder, and the castings F, and terminate in a head, o. These sudsing-boards are provided with alternate ribs p and line of perforations q, the ribs p of each board being opposite the perforations q upon the other, to add greater power upon the clothes by throwing them in a corrugated position when acted upon by the revolution of the cylinder. The rods I pass down along the faces of the sudsing-boards H, to which they are secured, and pass through a slot, K, in the cylinder, said

slot being protected by clips *r*. These rods are provided at their lower ends with rollers *s*, which give a rolling friction upon the clips *r* and cams *E* when the cylinder is revolved, 5 to prevent wear. When the cylinder is rotated the rollers *s* operate against the cams to draw the sudsing-boards toward the center, and thereby compress the clothes in the said cylinder, the cams being adjusted to or from 10 the center of the boiler by means of an elongated slot, *t*, therein, and set-screw *u* engaging with a hole in the seat *h* of the casting *C*, the elasticity of the clothes forcing the said sudsing-boards back when the rods have ceased 15 to act upon the cams. At each revolution of the cylinder the clothes change their places and are constantly acted on by the forcing out of the dirty suds and again receiving a fresh supply of water through the ports *w* 20 formed by a V-shaped plate being set in between the walls of the cylinder below openings upon its periphery, and the clothes being acted upon by the compressing and releasing of the sudsing-boards operated by the rods 25 and cams the dirty water is forced out with greater effect than it could be done by the weight of the clothes alone. Also, the ribs of one sudsing-board being opposite the perforations of the other, greater power is exerted 30 upon the clothes by throwing them in a corrugated position.

By the construction of a boiler washing-machine as above described I am enabled to do a large amount of washing with the use of but 35 little water, thereby making a saving in fuel, while at the same time the clothes being constantly agitated and changing their position in the cylinder by its revolutions and the action of the sudsing-boards thereon they are 40 washed more thoroughly and rapidly than by the ordinary machines now in use. After washing the clothes they may be thoroughly rinsed by placing clean water in the boiler and rotating the cylinder the same as for washing, the 45 clean water being forced through every particle of the clothes, thereby removing all suds and sediment.

Having now fully described my invention, what I claim as new, and desire to secure by 50 Letters Patent, is—

1. In a steam-boiler washing-machine, the

casting *C*, having vertical arms *e*, terminating in journal-bearings *f*, horizontal piece *d*, and seats *h*, in combination with the cams *E*, substantially as and for the purpose set forth. 55

2. In a steam-boiler washing-machine, the combination, with the cylinder *D*, having rods *I*, extending beyond its periphery and carrying rollers *s*, of the adjustable cams *E*, connected to each side of the vessel or tank *A*, 60 near the bottom thereof, substantially as and for the purpose specified.

3. In a steam-boiler washing-machine, the combination, with the cylinder *D*, having removable section *G*, of the castings *F* and radial arms *i* upon each side of the cylinder, said arms terminating at their outer ends in a right-angle bend or toe, *k*, to overlap the cylinder, one of said arms upon each of the castings having connected thereto a removable rod, *m*, substantially as and for the purpose set forth. 70

4. In a steam-boiler washing-machine, the rods *I*, secured to the castings *F*, and passing through the cylinder *D* and sudsing-boards *H*, and extending down the faces of the said sudsing-boards through a slot, *K*, in the cylinder, and having rollers *s* upon their ends, in combination with the cams *E*, against which they operate to give a rolling friction, substantially 75 as shown and described.

5. In a steam-boiler washing-machine, the cylinder *D*, made in two sections, provided with ports *w*, constructed in the manner described, slot *K*, and sudsing-boards *H*, said cylinder being held and braced between the 85 castings *F*, and rotated on journals secured in sockets upon the said castings revolving in the bearings *f* of the casting *C*, substantially as specified.

6. In a steam-boiler washing-machine, the 90 boiler *A*, having secured to its bottom the casting *C*, in combination with the cylinder *D*, castings *F*, sudsing-boards *H*, rods *I*, and cams *E*, all arranged to operate substantially as and for the purpose set forth.

In testimony that I claim the above I have hereunto subscribed my name in the presence of two witnesses.

LEMUEL STEELY BETZER.
